UNITED STATES PATENT OFFICE

JOHN W. RAU, OF CHICAGO, ILLINOIS, ASSIGNOR TO MARSHALL FIELD & COMPANY, OF CHICAGO, ILLINOIS, A CORPORATION OF ILLINOIS

DESIGN FOR A TEXTILE FABRIC OR SIMILAR ARTICLE

Application filed June 4, 1928. Serial No. 26,987. Term of patent 3½ years.

To all whom it may concern:

Be it known that I, JOHN W. RAU, a citizen of the United States, residing at Chicago, in the county of Cook and State of Illinois, have invented a new, original, and ornamental Design for a Textile Fabric or Similar Article, of which the following is a specification.

The accompanying drawing, forming part of this specification, is a view of a portion of a textile fabric bearing the design; the lining and shading on the drawing representing contrasting shades and colors.

I claim:

The ornamental design for a textile fabric or similar article, as shown and described.

JOHN W. RAU.
